BROODER HEATER

Abraham S. Friedman, Hicksville, Ohio, assignor
to The National Ideal Company, Toledo, Ohio,
a corporation of Ohio

Application November 12, 1952, Serial No. 22,244

Term of patent 7 years

(Cl. D12—2)

To all whom it may concern:

Be it known that I, Abraham S. Friedman, a citizen of the United States, and resident of Hicksville, in the county of Defiance, and State of Ohio, have invented a new, original, and ornamental Design for a Brooder Heater, of which the following is a specification, reference being had to the accompanying drawing, forming a part thereof.

In the drawings, Fig. 1 is a perspective view of a brooder heater, with the suspension chains shown in dotted lines, embodying my new design.

Fig. 2 is a side elevation thereof, and

Fig. 3 is a top plan view thereof.

The dominant features of my design are shown in full lines.

I claim:

The ornamental design for a brooder heater, substantially as shown and described.

ABRAHAM S. FRIEDMAN.
